[57] CLAIM

The ornamental design for a coin holder for an automobile dashboard, as shown and described.

DESCRIPTION

FIG. 1 is a top, front, and left side perspective view of a coin holder for an automobile dashboard showing my new design with the roll top in closed position; FIG. 2 is another top, front, and left side perspective view thereof with the roll top in open position and the magnet bottom cover shown in exploded view; FIG. 3 is a top plan view thereof; FIG. 4 is a right side elevational view thereof; and, FIG. 5 is a bottom plan view thereof. The rear of the design is unornamented.

FIG. 1

FIG. 2

FIG. 3

FIG. 4

FIG. 5
